UNITED STATES PATENT OFFICE.

HENRY W. O'NEILL, OF ELMHURST, NEW YORK, ASSIGNOR TO BELL TELEPHONE LABORATORIES, INCORPORATED, OF NEW YORK, N. Y., A CORPORATION OF NEW YORK.

TELEPHONE SYSTEM.

Application filed December 19, 1925. Serial No. 76,358.

This invention relates to telephone systems and particularly to improvements in methods and means for handling calls over toll and long distance lines.

5 In terminating such lines, it is usually desired that provision be made for handling traffic at different switchboards or positions. Certain positions provide for handling "incoming" calls, others for handling "outgoing" calls, others for making "through" connections, while special or "delayed" calls may be handled at certain other positions. Heretofore, all calls were received at inward positions, and such calls as were not to be 10 handled at these positions were transferred to other positions, depending upon the type of connection desired. In making such transfers, resort is usually had to local trunks or to signalling circuits local to the toll office 15 or switchboards.

It is the principal object of this invention to provide an improved method and system for more reliably and more economically handling telephone traffic of this general nature.

25 In attaining the above and other objects of this invention, the arrangement of devices and circuits is such that when a call is originated, alternating currents at chosen 30 frequencies will be automatically transmitted over the line for the selection and energization of a line signal at a particular group of positions at a distant toll center. Under this selective system, the attention 35 of an originating and a completing operator only is required, and a saving in line and operating time is thereby effected, that is, all 40 transfer operations heretofore required are eliminated.

45 In carrying out the present invention, a line circuit is connectively accessible to link circuits at a plurality of points within each exchange center. In originating a call, alternating currents over a so-called sleeve conductor which is local to an exchange equipment, effect frequency selection of currents which become effective through a signal transmitter of a link circuit by way of a line, to energize one of a plurality of signals. 50 This signal thereby selectively calls a particular group of positions or a particular station at a distant exchange point. Each link circuit is also provided with a signal so coordinated with the line equipment that when a connection is made, this signal is

universally controlled irrespective of the frequency of arriving signalling currents.

This invention is diagrammatically illustrated in the accompanying drawing in which Fig. 1 shows the terminating equipment at one end of a line and portions of a cord circuit arranged in accordance with this invention, while Fig. 2 shows a modified form of the cord circuit portions of Fig. 1.

55 In the drawing, A indicates such portions of a cord circuit as may be necessary for a clear understanding of this system; B indicates equipment that may be common to a plurality of cord circuit; C indicates a plurality of sources of alternating current of different frequencies that may be common to the equipment B, while D indicates terminating equipment of a line circuit E. The latter equipment comprises jacks 2, 3, 4 and 5, and corresponding line signals 12, 13, 14 and 15, local circuit relays 7 and 11, line relays 25, 26, 27, 28 and transformers 30, 31 and 32 connected in the sleeve conductors of the jacks 3, 4 and 5, respectively.

70 For convenience of description, let it now be assumed that a duplicate equipment of that shown in the drawing is present at the distant end of this line circuit E, so arranged that so-called two-way service may be carried out over this line, and so arranged 75 that the line signals 12 to 15, may be present at each switchboard or group of positions, while multiples of the respectively associated jacks will be present to render equivalent or 80 corresponding jacks accessible at each of the several position groups.

85 Let it now be assumed that it is desired to call and extend a connection to a group of positions, corresponding to jack 2 and signal 12. To accomplish this an operator 90 may insert a plug 1 of the cord circuit A into the jack 2, thereby completing a local circuit from grounded battery, winding of relay 6, sleeve terminals of plug 1 and jack 2, winding of relay 7 to ground. This causes 95 the operation of relay 6, which completes the tip conductor of the cord at its upper armature and front contact. The above circuit also causes the operation of relay 7, which 100 in operating its outer lower armature removes the battery shunt from the winding of relay 11. The resistance of the winding of the relay 11 is such as to prevent the operation of any of the lamps 12, 13, 14 and 15 on the operation of any of the combina- 105 110

tions of the relays 25, 26, 27 and 28 as will hereinafter be described.

The calling operator now actuates her ringing key 10 to cause the lighting of a lamp corresponding to lamp 12 at the desired position at the exchange in which the opposite end of trunk E terminates. On the operation of this key, alternating currents from the sources 20 and 21 of different frequencies are transmitted over the tip and ring conductors of trunk E and cause the operation of relays corresponding to relays 26 and 25 respectively at the distant end of the trunk. The circuits for these currents are as follows: from ground, through the alternating current source 20, right hand armatures and back contacts of relays 44 and 42, through the inner upper closed contacts of key 10, upper armature and front contact of relay 6, tip terminals of plug 1 and jack 2, over the tip conductor of trunk E through relays corresponding to relays 25, 26, 27, and 28 and a condenser corresponding to condenser 29 in series at the distant end of the trunk, back over the ring conductor of the trunk to the originating exchange, ring terminals of jack 2 and plug 1, the lower closed contacts of key 10, right hand armature and back contact of relay 47, through alternating current source 21 to ground. Relays 25, 26, 27 and 28 and the corresponding relays at the distant end are alternating current responsive relays that respond to different frequencies, and the relay 26 and its corresponding relay at the distant end are of such character as to operate in response only to alternating current from source 20, while relay 25 and its corresponding relay at the distant end are of such character as to operate in response only to alternating current from source 21. The operation of the relays corresponding to relays 25 and 26 at the distant end close a circuit through their lower armature and front contacts as follows: battery, lower armature and back contact of the relay corresponding to relay 7, lower armature and front contact of the relay corresponding to relay 26 and through the lower winding of this relay through the lamp corresponding to lamp 12 at the operator's position at the distant exchange through the lower winding of the relay corresponding to relay 25 and through the lower armature and front contact thereof, through the inner armature and back contact of the relay corresponding to relay 7 to ground. This circuit causes the lighting of the lamp corresponding to the lamp 12 and the operator at that position will thus be notified that a connection requiring her attention is desired.

It will be noted that relays 25 and 26 will also operate on the application of currents from sources 20 and 21, but as relay 7 is operated, no circuit will be completed for lamp 12 at this call originating exchange at this

time. The relays corresponding to relays 25 and 26 at the distant exchange are now locked up through their lower windings under control of the relay corresponding to relay 7.

The positions at the distant exchange are equipped with cord circuits such as A, and the operator at the called position on noting the lighted condition of the lamp associated with the trunk E will insert the answering plug of a cord into the corresponding jack. This closes a circuit for the operation of relays corresponding to relays 6 and 7 at that exchange, and on the operation of the latter relay the battery at the lower outer armature thereof will be removed from the locking circuits thereby releasing the relays corresponding to relays 25 and 26 and consequently the lamp corresponding to lamp 12 will be extinguished.

The operators at both ends of the trunk E may now operate their listening keys such as 52 and the communication of the desired subscriber's number from the operator at A to the operator at the distant exchange may now take place. When the operator at the distant exchange has completed a connection to the wanted subscriber and conversation between the calling and the called subscriber has terminated, the operator at either exchange may transmit a signal to the other operator for any supervisory purpose, for example, a signal to signify that the connection may be taken down.

If it is assumed that the operator at the distant end actuates her ringing key current from sources corresponding to sources 20 and 21 will be transmitted back over the trunk E to the originating operator's position to cause the operation of relays 25 and 26 in the same manner as when current from the sources 20 and 21 was transmitted to the distant exchange as hereinbefore described. In this case, the operation of relays 25 and 26 does not result in the lighting of lamp 12 as relay 7 is operated, but it should be noted that in this case, relay 11 will operate over a circuit as follows: battery, winding of relay 11, armature and front contact of relay 26, lower winding of relay 26 through lamp 12, lower winding of relay 25, armature and front contact thereof to ground at the upper armature and front contact of relay 7. The operation of relay 11 causes a circuit to be closed as follows: from ground through alternating current source 21, armature and front contact of relay 11, sleeve terminals of jack 2 and plug 1, lower outer normally closed contacts of key 10, winding of alternating current responsive relay 50, lower armature and front contact of relay 6, through battery to ground. Relay 50 responds to current from this alternating current source, and on the operation of this relay a circuit is closed for the lighting of the

supervisory lamp 51 as follows: battery, lower armature and front contact of relay 6, winding of relay 50, armature and front contact thereof, through lamp 51 to ground 5 at the upper closed contacts of talking key 52. This circuit causes the locking of relay 50 and the lighting of lamp 51 under control of relay 6. The lighting of this lamp 10 may indicate to the operator at A that the connection is to be taken down or that the operator at the distant exchange desires to communicate with the operator at A. When the operator at A finds the lamp 51 lighted, she may operate talking key 52 to connect 15 her telephone set with that of the operator at the distant exchange or if the signal is to be interpreted as a disconnect signal, she will simply remove plug 1 from jack 2. In either case it is obvious that relay 50 will 20 release and lamp 51 will be extinguished.

If it is decided to extend the connection to a certain different position at the distant exchange, the operator at A inserts plug 1 into jack 3. Relays 6 and 7 are operated in the 25 same manner as before. It will be noted that a different combination of frequencies are transmitted in this case and this is accomplished in a different manner from that of the former case. On the insertion of plug 30 1 into jack 3, operation of relay 7 and actuation of the ringing key 10, a circuit is closed as follows: from ground, through alternating current source 24, primary winding of repeating coil 30, middle lower armature and front contact of relay 7 to ground. Current 35 from this source 24 induces through the secondary winding of repeating coil 30 an alternating current of the same frequency, and a circuit for this induced current may be traced as follows: from ground through the upper winding of repeating coil 40, lower outer closed contacts of key 10, sleeve terminals of plug 1 and jack 3, secondary winding of repeating coil 30, armature and back contact of relay 11 to ground. The current 40 through this circuit will induce in the secondary of repeating coil 40 an alternating current of the same frequency. A circuit for this path may be traced from ground 45 through the relay 41, which is designed to respond to currents of this frequency only, and through the secondary winding of repeating coil 40 to ground. Relay 41, in responding, opens the circuit through its armature and back contact, which it will be noted 50 shunts the winding of relay 42, so that relay 42 will now operate over a circuit as follows: battery, armature and back contact of relay 43, winding of relay 42, armature and back contact of relay 46, upper outer closed contacts of key 10 to ground. Due to the operation 55 of relay 42 alternating currents will now be transmitted from sources 24 and 21. That is, alternating current from source 21 will 60 be transmitted through the armature and

back contact of relay 47 through the lower inner closed contacts of key 10 to the ring conductor of trunk E, while alternating current from source 24 will be transmitted through the armature and front contact of relay 42, through the upper inner closed contacts of key 10 to the tip conductor of trunk E. 70

In this case, therefore, a relay at the distant exchange corresponding to relay 25 will 75 respond to current from source 21 while a relay at the distant exchange corresponding to relay 27 will respond to current from source 24. The operation of these relays closes a circuit for the operation of a lamp 80 corresponding to lamp 13 at the called position at the distant exchange. This circuit may be traced as follows: Battery, the lower outer armature and back contact of a relay corresponding to relay 7, the lower armature 85 and front contact and lower winding of a relay corresponding to relay 27, a lamp corresponding to lamp 13, lower winding, armature and front contact of a relay corresponding to relay 25, the upper normal 90 contact and armature of a relay corresponding to relay 7 to ground. In this case, therefore, by the combined action of inserting plug 1 into jack 3 and operating key 10, the lamp at the called position at the distant 95 exchange will be lighted.

In a similar manner another position at the distant exchange may be selected by inserting plug 1 into jack 4. In this case relays 6 and 7 operate as before, and a circuit 100 in this case is completed from alternating current source 23 through the primary winding of repeating coil 31 to the middle armature and front contact of relay 7 to ground. Current from this source which is of a different frequency than the current from the other sources, will induce in the secondary of repeating coil 31 a current of the same frequency, and a path for this current may be traced as follows: ground, upper winding 105 of repeating coil 40, lowermost closed contacts of key 10, sleeve terminals of plug 1 and jack 4, secondary of repeating coil 31, armature and back contact of relay 11 to ground. The current through the primary 110 of repeating coil 40 induces a current of the same frequency through the secondary of this repeating coil, and in this case relay 43 will respond as it is designed to respond only to current of this particular frequency. The circuit for the current through the winding of this relay from the secondary of the repeating coil 40 is obvious. Operation 115 of relay 43 opens the short-circuit around the winding of relay 44 so that this relay will now operate over a circuit as follows: battery, winding of relay 44, armatures and back contacts of relays 41 and 46, uppermost closed contacts of key 10 to ground. Operation of relay 44 permits current from 120 125 130

source 23 to be transmitted through its armature and front contact, the armature and back contact of relay 42 to the tip conductor of the trunk, while current from source 21 5 will be transmitted as hereinbefore traced to the ring conductor of the trunk.

- In this case a relay at the distant exchange corresponding to relay 25 will be operated in response to current from source 21 and a 10 relay corresponding to relay 28 will be operated in response to current from source 23. A circuit for the operation of a lamp corresponding to lamp 14 will be completed and may be traced as follows: Battery, lower 15 armature and back contact of a relay corresponding to relay 7, armature and front contact and lower winding of a relay corresponding to relay 28 through a lamp corresponding to lamp 14, lower winding, armature and front contact of a relay corresponding to relay 25, lower inner armature and back contact of the relay corresponding to relay 7 to ground. It will thus be clear that when the operator at A inserts the plug 20 25 1 into the jack 4 and operates the ringing key 10, current from sources 21 and 23 will be transmitted over the trunk E to energize a lamp at a corresponding position at the distant exchange.
- 30 To light a lamp at a fourth position the operator at A may insert plug 1 into jack 5. In this case, the operation of relay 7 and the operation of key 10 causes the transmission of currents from sources 20 and 24 as follows: On the operation of relay 7 a circuit 35 will be closed from source 21, through the primary of repeating coil 32, middle armature and front contact of relay 7 to ground. Current from this source will induce a current of the same frequency in the secondary of repeating coil 32 and a circuit for this induced current may be traced as follows: from ground through the primary of repeating coil 40, lower outer closed contacts of 40 key 10, sleeve terminals of plug 1 and jack 5, secondary of repeating coil 32, armature and back contact of relay 11 to ground. This current through the primary of repeating coil 40 induces a current of the same 45 frequency through the secondary of this coil, and in this case, relay 46 will be the relay responding to the current of this frequency. Relay 46 in operating removes the shunt around the winding of relay 47 so that this 50 relay will now operate over a circuit that may be traced from ground, armatures and back contacts of relays 41 and 43, winding of relay 47, upper outer closed contacts of key 10 to ground. It will be noted then that on the operation of relay 47 current from source 24 will be transmitted through the armature and front contact of relay 47 to the ring conductor of trunk E while current from source 20 will be transmitted 55 through the armature and back contact of 60 relay 44 and 42 to the tip conductor of trunk E.
- 65 In this case the relay corresponding to relay 26 at the distant exchange will respond to current from source 20, while the relay corresponding to relay 27 will respond to current from source 24. A circuit will thereby be completed for the operation of a lamp corresponding to lamp 15 as follows: Battery, lower outer armature and back contact 70 of the relay corresponding to relay 7, armature, front contact and lower winding of relay 26, and from this battery through the armature, front contact and lower winding of the relay corresponding to relay 27 in 75 parallel, through the resistances corresponding to resistances 34, through a lamp corresponding to lamp 15, lower armature and back contact of the relay corresponding to relay 25, through the lower inner armature 80 and back contact of the relay corresponding to relay 7 to ground. The lighting of the lamp corresponding to lamp 15 at the "night" operator's position will thus result from the combined operation on the part of 85 the operator at A of insertion of plug 1 into jack 5 and the actuation of key 10.
- 90 It is evident from the above description that an exceedingly simple arrangement has been provided by this invention for selecting 95 different positions at a distant exchange over which a connection may be extended, that is, all that the operator at the call originating exchange has to do is to select a jack corresponding to the position desired at the distant end, insert the plug of a cord circuit into this jack and operate her ringing key. It is also evident that by this arrangement 100 calls may be transmitted and received in both directions over the trunk E and that 105 after a connection has been established supervisory operations may be performed by simply operating the ringing key in the usual manner.

The modification shown in Fig. 2 is identical with the disclosure of the invention in Fig. 1 with the exception that in place of the alternating current sources 21, 23 and 24 alternating current source of the vibratory relay type have been substituted and 110 arranged to supply currents of different frequencies to the cord and trunk circuits through repeating coils such as 60, 61, 63 and 64. These vibratory relays may receive current for operation only when a plug is 115 inserted in a jack of a trunk such as E and when the key 10 is operated or when relay 11' is operated. Relay 11' is the same as relay 11 except that a special armature and a contact to ground is provided. A relay 65 120 is therefore operated each time key 10 or relay 11' is operated to supply a ground connection for the vibratory relays 66, 67, 68 and 69, and also for the operation of relays 42, 44 and 47 as hereinbefore described. To 125 130

trace one of these circuits, for example, the circuit for vibratory relay 66, when relay 65 is operated, current will be supplied from battery, primary winding of repeating coil 5 60, through the windings of the two coils of relay 66 in series to ground at the armature and front contact of relay 65. The operation of relay 66 in response to this current will cause its armature to be operated towards 10 the right and thus short-circuit its own windings. In this manner, relay 66 is alternately operated and released, and consequently an alternating current is induced in the secondary winding of repeating coil 60 corresponding 15 in frequency to the frequency of the operation and release of relay 66. These vibratory relays are therefore designed to cause alternating currents of different frequencies to be supplied through the repeating coils 60, 61, 63 and 64 respectively for 20 use in selecting various positions at the distant exchange.

What is claimed is:

1. In a signaling system, line circuits, a 25 cord circuit and a signaling key therefor, means for connecting said cord circuit to said lines, a plurality of sources of current of different frequencies, a plurality of tuned relays, a plurality of transformers for each 30 said line circuit, and circuits controlled by said key for applying current from said sources by way of the transformer of a connection to select certain of said tuned relays, and relays controlled by said certain tuned 35 relay for selectively applying energy at predetermined frequencies from said sources to said key.

2. In a signaling system, a line having a 40 plurality of connectively accessible points, a plurality of current sources of different frequencies, a link circuit for extending connections from said line, a signal transmitter for said link circuit, and frequency controlled means for selectively rendering currents from said sources effective with said transmitter according to the connective point to which said link circuit may be joined.

3. In a signal transmitting system, a link 45 circuit including a signal transmitter, sources of current having a plurality of frequencies, a line having a plurality of connective points for said link circuit, frequency controlled means for selectively applying said frequencies to said transmitter, and means 55 associated with said connective points to render said transmitter effective to control said frequency controlled means.

4. In a system of selective signaling, a link 60 circuit and a signal transmitter therefor, a line having a plurality of connective points for joining said link circuit to said line for signaling thereover, sources of current of different frequencies, frequency responsive means for selectively applying current of 65 different frequencies to said transmitter,

and means respectively associated with said connective points to render said transmitter effective to control said frequency responsive means.

5. In a signal receiving system, a line having a plurality of connectively accessible points, a line signal corresponding with each of said points, frequency controlled relays selectively responsive in pairs for individually controlling a corresponding signal, a link circuit for establishing connections at said points, a signal for said link circuit, and means responsive to the connection of said link circuit at any connective point for disabling said line signals while enabling response of the signal of said link circuit in response to any selected combination of said frequency controlled relays. 70 75 80

6. In a system for signaling by means of currents at different frequencies, line circuits, a signal transmitter, means for connecting said transmitter to said lines, sources of alternating currents at a plurality of frequencies, and frequency controlled means rendered effective by the connection of the transmitter to a line for selectively controlling the association of current frequencies with said transmitter. 85 90

7. In a signal transmitting system, a plurality of normally inert vibrators for producing alternating currents at different frequencies, line circuits, a signal transmitter, means for connecting said transmitter to said lines, frequency selecting circuits prepared under a connection between said transmitter and line circuit, and means under control of said transmitter to energize the vibrators for supplying said transmitter with signaling currents. 95 100 105

8. In a telephone exchange system, line circuits comprising main conductors terminated in respective exchanges, an additional conductor associated with the line conductors in said exchanges, a plurality of signals for each line, sources of alternating currents of different frequencies, transmitting means for applying permutations of said frequencies over said lines to selectively control said signals, and means selectively responsive to energy from said sources by way of the additional conductors for automatically selecting predetermined frequencies from said sources for said transmitting means. 110 115

9. In a telephone system, two conductor line circuits each having a third conductor individual thereto at each end thereof, link circuits provided with three conductors for extending connections from the three conductors of said terminating line circuits, signal transmitting means for each link circuit, a plurality of signals for each line at each exchange equipment, sources of current at a plurality of frequencies, and means for applying currents from said sources over the third conductor of one exchange equipment 120 125 130

for automatically energizing said transmitting means with current at frequencies to predeterminedly select one of said signals of a line at a distant exchange equipment.

- 5 10. In a telephone system, a line circuit, exchange equipment comprising connective points served by main and local conductors for terminating said line, link circuits for inclusion with said connective points, a signal receiving system for said main conductors, sources of direct current, sources of alternating current of different frequencies, electro-responsive means controlled by the direct current over said local conductor for predeterminedly affecting said signal receiving system, a signal transmitter for said link circuits, and electro-responsive means controlled by alternating current superimposed over said local conductor for selectively energizing said signal transmitter from said sources of alternating currents.
- 15 20. In a telephone system, exchange equipment including a pair of conductors for terminating a line, an additional conductor local to said exchange equipment, signal receiving means for said pair of conductors, a link circuit for inclusion with said pair and said additional conductor, a signal receiving system for said link circuit, means

for applying direct current over said additional conductor for controlling the receiving system of said pair, and means for superimposing alternating current over said additional conductor for controlling the signal receiving system of said link circuit.

35

12. In a telephone system, a trunk line having a corresponding plurality of connecting points at each end thereof, a signal individual to each connecting point at each end thereof, tuned relays for actuating said signals at each end thereof, a cord circuit, a signal transmitter associated therewith comprising a plurality of sources of alternating currents and means in said cord circuit selectively responsive to the particular connecting point of said trunk line with which said cord circuit is temporarily associated for switching into operative relation with said signal transmitter, certain of said sources of alternating current to actuate a signal at the distant end of said trunk corresponding to the particular connecting point with which said cord circuit is connected.
